UNITED STATES PATENT OFFICE.

LEVI K. FULLER, OF BRATTLEBOROUGH, VERMONT, ASSIGNOR TO J. ESTEY & CO.,
OF SAME PLACE.

DESIGN FOR A PARLOR-ORGAN CASE.

Specification forming part of Design No. 5,299, dated October 3, 1871.

To all whom it may concern:

Be it known that I, LEVI K. FULLER, of Brattleborough, in the county of Windham, and State of Vermont, have invented and produced a new and original Design for a Parlor-Organ Case, of which the following is a specification:

The nature of my design is fully represented in the accompanying photographic illustration, to which reference is made in this description; and consists, first, of circular or columnar projections connecting the front of the case with the consoles which support the key-board portion; second, in ornamented pilasters, in combination with the ends of the case.

The circular portions A A project from the plane of the front B at the inner angles of the consoles C C, starting with the base or pedestal of the latter and terminating with the top thereof, forming a graceful and easy gradation of surface from the plane of the front to the most prominent projections. The deeply-recessed angles are thereby agreeably modified.

The ornamented pilasters D D at each end of the case, starting from the base and terminating at the top, form characteristic ornaments for the ends, relieving them of the monotony of a plain or paneled surface.

I claim—

1. The design for an organ-case, consisting of the pilasters D D, in combination with the ends, as described.
2. The design for an organ-case, consisting of the curved projections A A and consoles C C, in combination with the front, as described.
3. The design for an organ-case, consisting of the curved projections A A, consoles C C, and the front, in combination with the pilasters D D and the end, as described.
4. The design for an organ-case, as shown and described.

In witness whereof I have hereunto signed my name in the presence of two subscribing witnesses.
